Primary Examiner — Zenia I Bennett(74) *Attorney, Agent, or Firm* — Suiter Swantz pc llo(57) **CLAIM**

The ornamental design for an inflatable water walkway, as shown and described.

DESCRIPTION

FIG. 1 is a perspective view showing our new design;
 FIG. 2 is a top plan view thereof;
 FIG. 3 is a front elevation view thereof;
 FIG. 4 is a left side elevation view thereof;
 FIG. 5 is a rear elevation view thereof;
 FIG. 6 is a right side elevation view thereof; and,
 FIG. 7 is a bottom plan view thereof.

The broken lines showing a valve, a left-side zipper flap, a right-side zipper flap, and a middle section of an inflatable water walkway of FIGS. 1-7 form no part of the claimed design.
